United States Patent Office

Des. 200,103
Patented Jan. 19, 1965

200,103

CAN OPENER

Alfred W. Madl, Mequon, Wis., assignor to John Oster
Manufacturing Co., Milwaukee, Wis., a corporation of Wisconsin

Filed Dec. 23, 1963, Ser. No. 77,892

Term of patent 14 years

(Cl. D22—2)

FIG. 1 is a perspective view of a can opener embodying my design;

FIG. 2 is a front elevational view thereof;

FIG. 3 is a top plan view thereof;

FIGS. 4 and 5 are side and rear elevational views, respectively thereof; and

FIG. 6 is a fragmentary sectional view taken along line 6-6 of FIG. 5.

I claim:

The ornamental design for a can opener, as shown.
